UNITED STATES PATENT OFFICE.

SEAMAN MILLER, OF NEW YORK, N. Y.

ORNAMENTAL TEXTILE.

1,406,208.

Specification of Letters Patent. Patented Feb. 14, 1922.

Application filed March 25, 1919. Serial No. 284,924.

To all whom it may concern:

Be it known that I, SEAMAN MILLER, a citizen of the United States, and a resident of the city of New York, in the county of New York and State of New York, have invented certain new and useful Improvements in Ornamental Textiles, of which the following is a specification.

This invention relates to tapestries or ornamental textiles used for the covering of walls and furniture and for curtains and hangings, and has for its main object to provide a method for making textiles of this character which shall successfully imitate the expensive hand made tapestries in which the artistic design is worked in by needle work and made an integral and continuous part of the fabric which is also formed by the needle.

Another object is to provide an ornamental textile of this character which shall successfully imitate the laborious and expensive tapestries made by hand, giving substantially the same artistic effect, in that the design seems to the eye to be worked into and integral and continuous with the fabric.

A further object is to provide an ornamental textile which shall have these properties and yet be inexpensive to make, by reason of economy in time and labor, whereby the finest storied tapestries may be placed in the hands of the average consumer, and yet afford him the same artistic value as the original all needle made tapestries aforementioned.

Other objects and advantages of this invention will appear from the detailed description and the features of novelty will be particularly pointed out in the claim.

In the drawing accompanying this specification, and forming a material part thereof,

Fig. 1 is a face view of a piece of ornamental textile made according to my invention;

Fig. 2 is an end elevational view corresponding to Fig. 1; and

Fig. 3 is a face view of an original all hand-needle made tapestry. It forms no part of the present disclosure but is made part of the drawing for the purpose of more clearly explaining the present invention.

Fig. 4 is a view on an enlarged scale of

the background of my fabric showing the arrangement of the warp and woof threads;

Fig. 5 is a similar view showing the needle-work superimposed upon the background to make up the ornamental design; 60

Figs. 6 and 7 are sections on line 6—6 and line 7—7 respectively of Fig. 5 showing the arrangement of the warp and woof threads of the background, the superimposed colored threads of the design being shown in section.

Fig. 8 is an enlarged view showing in detail the nature and arrangement of the warp and woof threads of the background 70 and some of the threads of the design in their relation to the background.

My invention will be best understood by referring first to Fig. 3 which shows the original tapestry that I have succeeded in 75 successfully imitating. This original tapestry is made by hand on a piece of canvas or other such material which serves as a background 10 for the needle work. The body of the textile surrounding and bordering the artistic design is made usually by "gros-point" 80 needle work 11 and the artistic design 12 is made by continuing the needle work so as to produce the desired ornamentation. Usually this ornament is produced by 85 "petit-point" needle work 13. The design 12 is thus practically woven into the fabric being an integral part thereof. Tapestries made in this way give a most artistic effect and have been for years regarded as the 90 finest ornamentation for house decorating purposes. But as will now be readily understood, to make them requires a most painful and laborious process, aside, of course, from expertness and great skill. As 95 a result, such tapestries are most expensive and far beyond the reach of the average householder.

In my present invention, I imitate this original hand made tapestry and materially 100 reduce the cost thereof, preferably in the following manner: The fabric or main body 14 of the tapestry is woven on a hand or otherwise operated loom especially adapted to produce a "gros-point" weave 14 to 105 simulate the "gros-point" needle work 11 of the original tapestry. This body portion may be woven on the loom in any size and then cut to desired lengths and widths. The woof threads 18 of said body portion 110

are maintained flat in the loom, while the warp threads 19 are passed over and under the alternate woof threads, the result being that the warp threads stand out above the 5 flat woof threads and hide the greater portion of said woof threads from view where- by the fabric is given the appearance of the "gros point" needle work used in hand- made tapestry backgrounds. I then produce 10 on a piece of the weave any desired artistic design such as 12' by "petit-point" needle work. This design it will be noted is super- imposed on the body portion 14 which serves also as a background for the needle- 15 work, thus eliminating the canvas 10. I prefer to use threads 20 of about the same size, material and general characteristics for the design as it used for the background, said thread being preferably the wide, coarse 20 thread ordinarily used in hand made tapestry, the superimposed threads for the design being drawn tightly on to the back- ground and stitched closely together prefer- ably by means of the cross stitch shown to 25 hide said background. By thus drawing the threads down tightly, they appear to an observer as substantially flush or in the same plane with the back ground, thus giving the desired effect or simulating or im- 30 itating the original hand-made tapestry. In Fig. 2 it will be seen that the design is slightly raised from the body as at 16, and the crossing of the threads of the needle work is shown on the rear of the body at 35 17. While the design is thus not flush with the body it nevertheless seems to the eye to be a continuous and integral part thereof and looks no different from the original tapestry such as shown in Fig. 3. I have 40 found that to best produce a successful imitation, this main body 14 should be woven from dark material. A combination of black and dark brown proves very effective, and tapestries made according to my

invention on such dark colored "gros-point" 45 woven backgrounds have actually deceived the eye when placed in juxtaposition to an original piece of tapestry, to such an extent that it could not distinguish the original from the imitation. 50

When ornamental textile made according to my invention is used to cover furniture or for the like purposes, the imitation becomes more and more successful as it is used, 55 since the superimposed design is flattened and gradually becomes more nearly flush with the body.

It will be clear that by providing the woven body portion in the manner set forth, I economize time and labor and reduce the 60 amount of skilled or expert work required in making the original tapestry, thus reducing the cost considerably and also making it possible to produce in large quantities and at a rapid rate. 65

Having thus described my invention, I claim as new and desire to secure by Letters Patent:—

In an ornamental tapestry, a loom-woven background comprising wide coarse woof 70 threads lying substantially in the same plane, and warp threads passing over and under alternate woof threads respectively, the parts of said warp threads passing over said woof threads upstanding above the 75 latter so as to cover substantially the greater part thereof, and ornamental petit-point embroidery comprising close-lying threads of the same coarseness as, and substantially similar to, the threads used in said back- 80 ground superimposed upon said background and drawn tightly down thereon to appear substantially in the same plane as said back- ground.

Signed at New York city, in the county 85 of New York and State of New York, this 19th day of March, A. D. 1919.

SEAMAN MILLER.
